(57) **CLAIM**

The ornamental design for a control panel, as shown and described.

DESCRIPTION

2.1 is a front perspective view of a control panel;
2.2 is a top view thereof;
2.3 is a bottom view thereof;
2.4 is a left-side view thereof;
2.5 is a right-side view thereof;
2.6 is a rear view thereof; and
2.7 is a front view thereof.
 Broken lines depict portions of the control panel that form no part of the claimed design.

1 Claim, 7 Drawing Sheets
